UNITED STATES PATENT OFFICE.

GUGLIELMO MARCONI AND WILLIAM SNOWLEY ENTWISTLE, OF LONDON, ENGLAND,
ASSIGNORS TO MARCONI WIRELESS TELEGRAPH COMPANY OF AMERICA, OF NEW
YORK, N. Y., A CORPORATION OF NEW JERSEY.

TRANSFORMER FOR HIGH-FREQUENCY CURRENTS.

1,246,973.

Specification of Letters Patent. Patented Nov. 20, 1917.

Application filed May 23, 1914. Serial No. 840,424.

To all whom it may concern:

Be it known that we, GUGLIELMO MARCONI, a subject of the King of Italy, and WILLIAM SNOWLEY ENTWISTLE, a subject of the King of Great Britain, both residing at Marconi House, Strand, London, England, have invented new and useful Improvements in Transformers for High Frequency Currents, of which the following is a specification.

This invention relates to transformers for use with high frequency, that is radio frequency, electric impulses and the object is to provide a transformer for the high power radio signaling apparatus used for transoceanic signaling.

It is well known that high frequency alternations are confined to the surface of the conductor and that a stranded conductor is best adapted for use with such currents. The primary coil here shown and described is five or six or more feet in diameter and is associated with a secondary coil located inside the ring or circle formed by the primary or it may be the secondary is outside the primary or it may be at one side of said primary. We use a non-magnetic core and the stranded conductor, a series of insulated strands, is helically disposed, preferably one layer and one single, helical convolution extending from end to end of the core. The core is divided at one point, like a split ring, thus affording means for connecting the stranded conductors to separated conducting plates at the terminals of the conductors, said conductors being thus connected electrically in parallel. The advantage of this helical arrangement is that no matter where the secondary coil is located with respect to the primary the inductive action of the exposed surface of one coil on the other coil is equal for each and every strand on the conductor formed of the series of strands.

Figure 1 is an edge view and Fig. 2 a side view of a large split ring primary with a single convolution made according to this invention. Fig. 3 is a section on the line 3—3, Fig. 2. Fig. 4 is an edge view and Fig. 5 a side view of a multiple arrangement of the primary coil. The scale of Figs. 4 and 5 is somewhat smaller than that of Figs. 1 to 3. In the examples shown the rings are

about five feet in diameter and one foot thick, but these dimensions may be varied very widely according to circumstances.

Each ring has a non-conducting core *a* preferably built up (as shown in section at Fig. 3) of boards glued together and connected by wooden pins. *b* are the insulated conductors, the ends of which are connected to terminal plates *c*. These conductors are merely indicated diagrammatically; in practice they touch each other and there are about one hundred and fifty of them, each consisting of a number of insulated wires 60 stranded or interwoven together into a cable in the manner commonly adopted in conductors of high frequency currents.

The drawings show the conductors only once twisted around each convolution of the 70 ring and this is generally the best arrangement, but they may be twisted twice or more around it but fractions of turns should be avoided.

The rings are preferably of circular section as shown.

What we claim is:—

1. In a high frequency current transformer a primary coil having a non-magnetic core in the form of a divided ring of 80 circular cross-section, a terminal at each end of the core and a helical conductor consisting of a series of insulated conductors helically disposed on said core, laid in parallel order, in a single layer, said series of conductors being electrically connected together at each terminal.

2. In a high frequency transformer a coil having a non-magnetic annular core of circular cross section and a series of insulated 90 conductors helically disposed, laid parallel to each other on said core, divided electrically and the divided conductors connected in parallel.

3. In a high frequency transformer a primary coil having a core of non-magnetic material, divided at one point, with a series of insulated conductors laid in parallel order on said core and electrically connected in parallel at the point of division of said core.

4. In a high frequency transformer a primary coil of laminated non-magnetic material in the form of a divided ring, circular

in cross-section, and a series of insulated conductor strands helically disposed in parallel upon said ring.

5. In a high frequency transformer a primary coil consisting of a split ring of non-magnetic material and a single layer of electrical conductors helically disposed upon said ring and divided at the ends of the split ring.

10. 6. In a transformer a primary coil having a non-magnetic split ring core and a single layer of insulated conducting strands helically disposed on said core.

7. In a transformer a primary coil having a non-magnetic split ring core circular in cross section and a layer composed of individually insulated conducting strands helically disposed thereon.

8. In a transformer, a primary coil having a non-magnetic split ring core, circular in cross section, with a series of insulated strands helically disposed in one layer and in one convolution extending from one end of said ring to the other.

25. 9. In a transformer a primary having a split ring core of laminated non-magnetic material and a layer of stranded conductors helically disposed.

10. In a transformer a primary having a

ring-shaped core of non-magnetic material 30 with free terminals, and a stranded conductor consisting of a series of separately insulated conductors helically disposed on said core, said conductors electrically connected in parallel and having free terminals coincident with the terminals of said core. 35

11. In a high frequency transformer, a primary coil consisting of a split ring of non-magnetic material having a terminal at each end thereof, and a single layer of electrical conductors helically disposed upon said ring and connected to said terminals. 40

12. In a transformer, a primary coil having a non-magnetic split ring core with a series of insulated strands helically disposed 45 in one layer and in one convolution, extending from one end of said ring to the other.

13. In a high frequency transformer, a primary coil provided with a substantially circular core having two free ends, and with 50 a series of insulated conductors laid in parallel order on said core and electrically connected in parallel at said free ends.

GUGLIELMO MARCONI.

WILLIAM SNOWLEY ENTWISTLE.
